UNITED STATES PATENT OFFICE.

ANDREW M. JOHNSON, OF INDIANAPOLIS, INDIANA.

CORD-ADJUSTER.

1,068,139.

Specification of Letters Patent.

Patented July 22, 1913.

Application filed March 5, 1910. Serial No. 547,411.

To all whom it may concern:

Be it known that I, ANDREW M. JOHNSON, a citizen of the United States, residing at Indianapolis, in the county of Marion and 5 State of Indiana, have invented certain new and useful Improvements in Cord-Adjusters, of which the following is a specification.

My invention relates to spherical cord adjusters, especially for electric light cord, 10 an object being to provide an efficient and convenient device of cheap and durable construction, a further object being to provide means for holding the cord and for releasing the pressure thereon at will so as to 15 make adjustments easily and without injury to the cord.

There are various cord adjusters in use but those that have come under my observation are either severe on the cord destroying 20 its insulation or do not retain it in adjustment.

In the accompanying drawings and following specification, my invention is more fully described and pointed out particularly 25 in the claim, and similar numerals indicating similar parts throughout the different figures of the drawings.

Figure 1 shows the adjuster in position 30 on a portion of the cord 10; Fig. 2 is a sectional view on line 2—2; Fig. 3 is a section on line 3—3; Fig. 4 is a section on line 3—3; Fig. 5 is a view of spring detached.

The different parts of my invention are represented by different numerals and 1 is 35 the body preferably of wood and spherical in form; 2, 2 are parallel cord openings equidistant from center of the ball shaped body; 3 is a spring opening through the center of the body and at right angles to 40 the cord openings 2, 2 and being preferably contracted in bore at 4, 4 to form an annular rib by which is retained the push button 5 provided with a suitable enlargement that said rib will hold it in place. The spring opening 3 is of such proportions that it will 45 cut equally into the openings 2, 2. The inner end of said push button 5 is provided with a conical recess 6, the apex of which points outwardly of the body and is adapted to 50 engage with the inwardly inclined end 7 of each of the springs 8 which are secured at opposite end to body in the present instance by having formed thereon a hook-shaped bend 9 and at which point they are 55 driven into said body or fastened in any

other suitable manner. The springs 8 lie in their normal position close to the edges of the opening 3, one at each side so that they will cut a considerable depth transversely into the bore of the openings 2, 2 as seen in Fig. 3 and where the movable ends 7 of said springs are seen to project slightly into the recess 6 of said push button so that when said button is pressed inwardly as shown in Fig. 4, said springs are 60 pressed toward each other at the points 7 within said recess 6 by which action the springs are also withdrawn from the bore of openings 2, 2; thus it is evident that when the cord is in place in this device as 65 is shown in Fig. 1 practically filling the openings 2, 2 and the springs 8, 8, are in their normal position as in Fig. 3, that said springs will press against the cord in both 70 said openings 2, whereby it is held in adjustment and vice versa, when it is desired to adjust it the push button is pressed in firmly with one hand when the adjustment of the 75 cord is readily effected by the other, and when pressure by the operator on the push button is released, the springs force the push button back to normal position and engage the cord again and retain adjustment.

It is evident that any adjuster that applies any friction whatsoever during adjustment, will in course of time when frequently adjusted cause wear on the insulation of the cord and finally expose the conductor, causing short circuiting of electric current or rendering the device dangerous 80 to the operator, and in my device there is no pressure whatsoever possible during adjustment of the cord.

In the application of my device there are 85 a number of deviations that may be resorted to and I desire to have it understood that I hold myself at liberty to make all such alterations or deviations from the exact form and construction here shown as fall fairly 90 within the spirit and scope of my invention 100 as claimed, and

What I claim as new and desire to secure by Letters Patent is:—

In a cord adjuster a suitable body having 105 a pair of parallel cord openings through said body and a spring opening through said body cross-cutting the plane of and between former said openings and cutting into the bore of each thereof, springs mounted in said spring opening adapted to lie across the 110

bore of said cord openings and adapted to normally press against a cord extending through latter said openings with suitable spring pressure, a push button with a reduced outer and a recessed inner end and longitudinally movable within said spring opening, the free ends of said springs engaging in said recess and shiftable toward

each other upon an inward movement of said button.

In testimony whereof I affix my signature in presence of two witnesses.

ANDREW M. JOHNSON.
